DESIGN FOR A DOLL

Ernest G. Fosbery, Ottawa, Ontario, Canada

Application June 25, 1937, Serial No. 70,056
In Canada February 26, 1937

Term of patent 14 years

To all whom it may concern:

Be it known that I, Ernest G. Fosbery, a citizen of the Dominion of Canada, residing in Ottawa, Canada, whose postal address is 18 Rideau Street, Ottawa, Canada, have invented a new, original, and ornamental Design for a Doll, of which the following is a specification, reference being had to the accompanying drawings, forming part thereof.

Figure 1 is a front view, Figure 2 a side view, and Figure 3 a back view of a doll, showing my new design.

I claim:

The ornamental design for a doll, as shown.

ERNEST G. FOSBERY.
